By his Atty. J. Dennis

United States Patent Office.

SIMON B. MOREY, OF SAN FRANCISCO, CALIFORNIA.

Letters Patent No. 97,952, dated December 14, 1869.

IMPROVEMENT IN PROPELLERS.

The Schedule referred to in these Letters Patent and making part of the same.

To all whom it may concern:

Be it known that I, SIMON B. MOREY, of the city and county of San Francisco, State of California, have invented an Improved Propeller-Wheel; and I do hereby declare the following description and accompanying drawings are sufficient to enable any person skilled in the art or science to which it most nearly appertains, to make and use my said invention or improvements without further invention or experiment.

My invention relates to such improvements in propeller-wheels for vessels as will effectually do away with the loss of power consequent on the use of the ordinary paddle-wheel, owing to the pounding and lifting of the water, as the buckets enter and emerge therefrom.

My arrangement of the wheel contemplates a sculling, or to-and-fro side motion, which is continuous and regular at all times, thus obviating any sudden strains.

In order to explain my invention, so that others can make and use the same, reference is made to the accompanying drawings, forming a part of this specification, in which—

A represents the propeller-shaft.

The wheels B and B are firmly secured to the shaft, at the proper distance apart, and may be made of any desired pattern or form, having a rim, D D'.

Between the outer rims D D' of the two wheels, I place a continuous spiral or screw-shaped piece of metal, E, which extends entirely around the wheels B and B. This screw is cut from metal, so as to leave a rim or screw-blade, of the proper width to act as buckets or paddles when the wheel is revolved in the water, and, when extended around between the wheels, a circular opening will be left, passing entirely around inside the screw.

The rims D D' of the wheels B and C should be united to this circular screw at about its middle, so that one half of the screw will be inside the rims, while the other half is outside.

In driving this wheel through the water, it makes

no difference whether the entire diameter of the screw is submerged or not.

When the entire diameter is beneath the surface of the water, the water will follow the screw as it passes through it, thus giving a constant and steady pressure at all times, while, after the screw has emerged, it will carry no water with it, as it would naturally fall from the sloping side of the screw as the wheel turned. The same would be the effect as the screw entered the water, thus doing away with the lifting and pounding which always accompany the use of the flat or horizontal buckets.

The spires of the screw may be made as far apart as desired, and in a wheel intended for a fast-running wheel, it would be better to give the screw long spires, as the resistance would be less, while the peculiar motion of the screw will give a greater speed for the power employed than any other form of buckets.

The buckets need not be continuous, but may be each made separate, and curved, and attached in such a manner that if completed or made continuous, a perfect spiral or screw would be formed, and when constructed in this manner, the wheel would give the same effect as when the same was continuous.

The action of the screw in the water will be similar to that employed in sculling a boat with an oar, as the screw moves from side to side of the wheel, and causes a similar driving-force to result.

What I claim, and desire to secure by Letters Patent, is—

The floats or buckets, formed by the convolutions of the circular spiral E, substantially as and for the purpose set forth.

In witness whereof, I have hereunto set my hand and seal.

SIMON B. MOREY. [L. S.]
